Robert L. Ray, Inventor
By C. Howes & Co., Attorneys.

UNITED STATES PATENT OFFICE

ROBERT L. RAY, OF ELIZABETHTON, TENNESSEE

REEL

Application filed April 9, 1929. Serial No. 353,727.

This invention relates to a reel on which the thread or other material is wound in the manufacture of artificial silk and any and all other materials in any kind of mills, the reel being designed to hold or support the thread while it is being treated.

The primary object of the invention is to provide a reel of this character so constructed that the blades thereof may move radially to the end that the diameter of the reel may be reduced and the thread easily removed from the reel without danger of damaging the thread.

Another object of the invention is to provide a reel of this character which may be contracted or expanded by an operator moving the supporting shaft of the reel longitudinally.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a reel constructed in accordance with the invention.

Figure 2 is a longitudinal sectional view of the reel.

Figure 3 is an end elevational view of the reel.

Figure 4 is a sectional view taken on line 4-4 of Figure 2.

Figure 5 is a fragmental detail view disclosing one of the reel heads and blade receiving notches thereof.

Figure 6 is a fragmental detail view of one of the blades illustrating the notch and securing pin at one end of the blade.

Figure 7 is a modified form of blade.

Referring to the drawings in detail, the reel includes heads 5 and 6 respectively, which heads are provided with notches 7 arranged in spaced relation with each other throughout the peripheries thereof.

In each of the notches 7 is an opening in

which a sleeve 8 is positioned, the sleeves being designed to receive the pins 9 that are carried by the blades 10, the pins 9 extending into the bottoms of the notches 11 formed in the blades 10. Thus it will be seen that movement of the blades longitudinally of the reel will be prevented at all times.

The heads are formed with square openings through which the shaft 12 slides in making an adjustment, the shaft being provided with reduced ends 13 that operate in suitable bearings of a reel supporting frame. As clearly shown by Figure 2 of the drawings, one end of each of the blades has its lower surface inclined as at 14 and provided with lateral grooves 15 defining ribs 16. The inner edge of each blade is provided with a cut out portion at 17 the edges of the blades adjacent to the cut out portions being grooved as at 18 defining ribs 19, which grooves and ribs are provided with straight end portions 20.

Rods 23 connect the heads and hold the heads in predetermined spaced relation with each other. Mounted for slidable movement with the shaft 12 are the blade adjusting disks 21 and 22 respectively, the disk 21 being provided with openings through which the rods 23 extend.

The disks 21 and 22 are secured to the shaft 12 by means of set screws 22' so that movement of the shaft 12 will result in a movement of the disks 21 and 22. Formed in the peripheries of the disks 21 and 22 are cut out portions so constructed that they define inwardly extended fingers 24 that fit within the grooves 15 and 18 and cooperate with the ribs 16 and 19 respectively to the end that as the disks 21 and 22 are moved longitudinally of the blades, the blades will be moved inwardly and outwardly.

Thus it will be seen that when the blades are in a position as shown by Figure 1 of the drawings, and it is desired to reduce the diameter of the reel, it is only necessary to move the shaft in the direction of the arrow as shown in Figure 2 with the result that the disks will be moved over the ribs, and since the ribs are inclined the blades will be drawn inwardly and the thread held on the reel may be readily removed.

The inner ends of the ribs are cut away as at 25 providing clearances so that when the disks are moved to positions opposite to the clearances, the blades may be removed or disengaged from the disks. A pin 26 is inserted in an opening formed in one wall of each cut away portion to normally restrict movement of the disks when the shaft 12 is moved to adjust the blades.

10 In the form of the invention as shown by Figure 7 instead of the blades being provided with grooves to provide ribs, the blade which is indicated at 10' is supplied with a strip 11' which is of a width to extend beyond the side faces of the blade to be engaged by the inwardly extended fingers of the adjusting disks.

I claim:

1. A reel of the class described, including heads, said heads having notches, and having openings in the bottoms of the notches, blades positioned in the notches and having pins extending into the openings to restrict movement of the blades longitudinally of the reel, inclined ribs formed on the blades, disks having notches, said notches including inwardly extended fingers embracing portions of the ribs, and means for sliding the disks to move the blades laterally to expand or contract the reel.

2. A reel of the class described, including heads, blades removably supported by the heads, said blade having inclined grooves formed in the sides thereof defining inclined ribs having substantially straight end portions, disks having notches defining inwardly extended fingers, embracing portions of the ribs to hold the blades against displacement, said fingers normally engaging said straight portions of the ribs, and said ribs being cut away at one of their respective ends to permit removal of the blades.

3. A reel of the class described, including heads, said heads having notches, blades fitted in the notches, pins carried by the blades, said heads having openings to receive the pins of the blades to restrict movement of the blades in one direction, a shaft extending through the heads, and means for transmitting movement of the shaft to the blades to move the blades laterally to expand or contract the reel.

In testimony that I claim the foregoing as my own, I have hereto affixed my signature.

ROBERT L. RAY.
